UNITED STATES PATENT OFFICE.

GEORGE J. KOSTERS, OF COVINGTON, KENTUCKY, ASSIGNOR TO THE STEWART IRON WORKS COMPANY, OF COVINGTON, KENTUCKY, A CORPORATION OF KENTUCKY.

VISITOR'S PARTITION FOR JAILS AND THE LIKE.

Application filed August 8, 1927. Serial No. 211,466.

In jails and the like there is usually a prisoner's corridor and a visitor's station, having a partition between them, so arranged that the prisoner and visitor may communicate with each other through the partition.

It is the object of my invention to provide novel means whereby this may be accomplished in such manner that the passage of objects between the visitor and the prisoner is prevented; further, to provide novel means for preventing unlawful or undesired passing of objects, such as files or other instruments, or other objects which might be unlawfully used by the prisoner, and of drugs, liquor and the like, by the visitor to the prisoner.

The invention will be further readily understood from the following description and claims, and from the drawings, in which latter:

Fig. 1 is a horizontal section, taken on the line 1—1 of Fig. 2, showing an exemplifying prisoner's corridor and visitor's station having my improved partition therebetween.

Fig. 2 is a front elevation of the same, partly in section on the line 2—2 of Fig. 1, and partly broken away, showing my improved partition.

Fig. 3 is an enlarged front elevation showing my improved partition, with various portions of the layers broken away, to expose the construction of the same.

Fig. 4 is a horizontal section of the same, taken in the plane of the line 4—4 of Fig. 3.

Fig. 5 is a vertical section of the same, taken in the plane of the line 5—5 of Fig. 3.

Fig. 6 is a vertical section of the same, taken in the plane of the line 6—6 of Fig. 3.

Fig. 7 is a cross-section of a detail of the same, taken on the line 7—7 of Fig. 2.

Fig. 8 is a horizontal cross-section, taken in the plane of the line 8—8 of Fig. 9, showing a modification of my improved device.

Fig. 9 is a vertical cross-section of the same, taken in the plane of the line 9—9 of Fig. 8; and,

Fig. 10 is a perspective view of an intermediate layer exemplifying a further modification of my improved device.

The arrangement of the prisoner's corridor and the visitor's station is optional, depending on the floor plan of the jail. The prisoner's corridor is instanced at 21, and the visitor's station at 22. My improved partition

is exemplified at 25, and may be conveniently located.

The partition comprises a pair of plates 31, 32. These plates are of resistant material, for instance steel, and one or both of the plates may be of tool-proof steel. The plate 31 may be designated the rear plate, or plate at the prisoner's side, and the plate 32 may be designated the front plate, or the plate at the visitor's side. The plate 31 is shown extending the full height of the partition and may be one of the main plates of the partition. Each of the plates is provided with a perforated portion 33 preferably extending over a small area thereof, which may be instanced as ten and three-quarters inches in width and four and three-quarters inches in height. There may be a number of these perforated portions. Three of the same as shown in Figs. 1 and 2 arranged side by side across the width of the visitor's station. The perforated portion may be designated the oral portion of the partition.

The holes 34 in the front plate and the holes 35 in the rear plate are in non-registry with each other. The holes in each plate are offset with relation to the holes in the other plate. The relative thickness of the plates, the diameters of the holes, and the offset distance between the holes, are preferably such, that the inner ends of the walls of said holes 35 and a right line drawn across the same will intersect, as shown by the dotted lines 36 in Fig. 4, so as to prevent an object being passed through said holes in a right line.

The respective plates are also provided with openings 37, 38, which register with each other. These are visual openings. They are preferably located in adjacency to the oral portions of the partition, and may be of similar area. Three sets of these visual openings are shown in Figs. 1 and 2. A shelf 39 supported on brackets 40 may be secured to the partition under the oral openings.

An intermediate layer 41 is located between the perforated portions of the front plate and rear plate. This intermediate layer is provided with perforations 42, and recurrent elevations 43 and depressions 44, shown formed by corrugating this intermediate layer. The corrugations may be of desirable width. The depths of the corrugations are preferably such that the intermediate layer fills the space between the front plate and the rear plate.

An intermediate layer extends throughout the area of each of the opposite perforated portions of said plates. It extends across the inner ends of the holes in the perforated portions of said plates. It forms recurrent walls extending transversely between the plates and, in connection with the walls of the holes in the plates, interferes with the passage of objects through the partition, while permitting the voice to pass therethrough, so that the visitor and prisoner may converse with each other. The diagonal portions of the intermediate layer are shown in the planes of the dotted lines 36 in Fig. 4.

15 The intermediate layer 41 is instances in the preferred embodiment of my invention as a sheet of steel provided with the perforations 42, which are substantially smaller than the holes 34, 35, in the plates 32, 31, and are 20 much closer together than said holes.

Transparent sheets 45 which are fracture resistant, are provided across openings 37, 38, in the outer plates of the partition. These sheets are preferably of bullet-proof glass. 25 They overlap the walls of said openings. The transparent sheets are shown thicker than the intermediate layers 41. To accommodate this greater thickness, the plate 32 is provided with forwardly sloping portions 46, 47, to 30 form an outwardly bulged portion 48.

Horizontal filler bars 49, 50, are provided between the plates. Vertical filler bars 51 are provided at the respective ends of the oral and visual sections. The vertical filler bars 35 are provided with enlargements 52 to fill the bulged portion 48 of the front plate.

Intermediate vertical filler bars 53 are located between the adjacent edges of the intermediate layers 41, and extend between the 40 lower horizontal filler bar 49 and the lower one of the intermediate horizontal filler bars 50. Intermediate vertical filler bars 54 are located between the adjacent edges of the glass sheets 45, and extend between the intermediate 45 horizontal filler bars 50. These bars are preferably of steel or resistant material. They form marginal walls for the spaces in which the intermediate layers 41 and sheets 45 are located, the areas of the spaces thus formed 50 being greater than the areas of the perforated portions and openings in the plates 31, 32. These marginal walls are preferably offset with relation to the margins of the perforated portions and the walls of the openings in the 55 front plate and the rear plate, for forming marginal recesses 56 in which the margins of said layers 41 and sheets 45 are received. A cushioning film 57 of cement may be located between the margins of the sheets 45 and the 60 walls of the recesses in which they are received.

The bars 49, 50, 51, are rigidly fixed to the plate 31, as by rivets 58. The plate 32 is secured to the bars preferably in such manner as 65 to be capable of removal, as by countersunk

screws 59, the countersunk screws being threaded into the bars, but not piercing the plate 31. This provides for security, as a guard is always present during the presence of a visitor, and it permits removal of the 70 plate 32 for repair or replacement of damaged parts, and for cleaning purposes.

The transparent sheets 45 are preferably arranged in a row above the series of oral portions 33 for convenient relation to the eyes and 75 mouth of the visitor and prisoner at the respective sides of the partition.

Instancing the structure as an example, but not as a limitation, it may be stated that the plate 31 is a plate of tool-proof steel of one-quarter inch thickness; that the plate 32 is a steel plate of three-sixteenths inch thickness; that the filler bars 49, 50, 53, 54, are three-eighths of an inch thick, which is the depth of the space between the plates 31, 32 80 at the oral portions thereof; that the holes 34, 35, are round holes three-eighths of an inch in diameter; that the intermediate layer 41 is a steel plate of No. 22 B. & S. gauge, and that the perforations therein are three-thirty- 85 seconds of an inch in diameter and their centers are seven-thirty-seconds of an inch apart, and that they are in staggered relation in the layer; that the holes in each of the plates 31, 32, are two inches apart at their centers, 90 and that the holes in each plate are offset equidistantly with relation to the holes in the other plate, the holes in each of the plates being opposite the body portions equidistant between the holes in the other plate; that the corrugations in the intermediate layer have the centers of their elevations or crowns on each side of the plate two inches apart, and that this intermediate plate is so placed between the front plate and the rear plate that 95 the crowns of the intermediate plate register with and are arranged crosswise of the holes in the respective outer plates.

Referring to Fig. 4 it will be noted that, when so arranged, right lines 36, drawn to 100 pass through adjacent openings in opposite outer plates, intersect the ends of the walls of the holes therethrough, and prevent the passage of an object in a right line through adjacent holes. It will be further noted that the slanting portions 60 of the intermediate layer between adjacent holes in opposite outer plates, are substantially in line with such right lines drawn through said adjacent holes, forming an interfering wall throughout the distance between said holes, preventing penetrating of the partition or the passage of any object therethrough.

Referring to said Fig. 4 it will be further noticed that, as indicated by the lines of arrows 61, the voice of the visitor at the visitor's station is projected through the hole in the plate 32 and through the perforations in the crown of the layer 41 extending across said hole; that said voice is reflected between 125 130

the proximate walls formed by the inner faces of the plates 31, 32, and through the perforations 42 in the slanting portion 60 of the layer between the hole 34 and the hole 35, 5 the voice rebounding through the perforations in the crown of the intermediate layer extending across the hole 35, to the prisoner's station. The prisoner's voice is conveyed in reverse direction to the visitor's side 10 of the partition.

I have in Figs. 8 and 9 shown a modification of my improved device, in which the intermediate layer 62 is formed of a perforated sheet of steel having oppositely extending depressions, forming bulges 63, 64, the crowns of which register with the respective holes in the opposite plates 31, 32, so that there is a crown extending across each hole in each of the plates, with perforations 65 in the intermediate layer registering with each of 15 said holes, and slanting portions 66 of the intermediate layer extending between holes in one of the plates and adjacent holes in the other of the plates.

I have in Fig. 10 shown a further modification of my improved device, in which the intermediate layer 71 is formed of perforate wire mesh which is corrugated similarly to the intermediate plate 41, as shown by the 20 elevations 92 and depressions 93, the interstices 94 between the wires serving as the perforations for this intermediate plate or layer. It may be stated as an exemplification but not as a limitation that the wire mesh 25 may be of No. 18 B. & S. gauge wire woven eight to the inch.

My improved construction provides ready means whereby the visitor and prisoner may see each other through the partition, and also 30 converse with each other through the partition, other communication however between the two, such as passing of saws or other tools, narcotics and liquor, being however prevented, and provides means for oral communication which are integral with the partition. It also provides a compact and exceptionally strong structure for the purpose 35 described.

Having thus fully described my invention, 40 what I claim as new, and desire to secure by Letters Patent, is:

1. A visitor's partition of the character described, comprising front and rear perforate plates and an intermediate perforate layer 45 between said plates extending across the perforations in said plates, said intermediate perforate layer formed with recurrent elevations and depressions and with slanting portions extending slantingly between perforations of opposite ones of said plates for the purpose described.

2. A visitor's partition of the character described, comprising front and rear perforate plates, the perforations of said front plate

and of said rear plate being in non-registry, 55 and an intermediate perforate layer formed into recurrent elevations and depressions, said intermediate perforate layer extending between said plates across said first-named perforations and having portions which extend in the directions and lie in the planes of right lines drawn between adjacent ones of said first-named perforations in opposite plates.

3. A visitor's partition of the character described comprising a front plate and a rear plate having a space therebetween, said front plate and said rear plate each provided with holes, the holes in said front plate and in said rear plate arranged in off-set relations so that the holes in each plate are opposed by the body portions of the opposite plate across said space, and an intermediate perforate layer in said space, the perforations of said intermediate layer being smaller than said holes, 80 said intermediate layer formed into recurrent oppositely extending elevations and corresponding depressions, adjacent ones of said oppositely extending elevations located proximate to and across the inner ends of adjacent holes respectively in said front plate and said rear plate and the plane of that portion of the body of said intermediate layer located between adjacent holes in opposite plates 85 extending in slanting direction between said adjacent holes in said opposite plates, for the purpose described.

4. A visitor's partition of the character described comprising a front plate and a rear plate having a space therebetween, said front plate and said rear plate each provided with holes substantially equally spaced apart, the holes in said plates arranged in off-set relation to each other so that the holes in each plate are opposite the body portions between holes of the opposite plate, and an intermediate perforate layer in said space between said plates, said intermediate layer formed with slanting perforate portions extending slantingly between said plates, and constructed and arranged whereby sound proceeding through the holes in one plate is deflected between said plates through the perforations of said intermediate layer and through the holes in the other of said plates.

5. A visitor's partition of the character described comprising front and rear resistant plates provided with opposite portions provided with holes, the holes in one plate being in non-registry with the holes in the other plate at such opposite portions of such plates, said plates being provided with registering observation openings in adjacency to said first-named portions, shatter resistant window sheets closing said openings, and an intermediate perforate layer provided with recurrent elevations and depressions between said first-named portions across said holes.

and slanting portions of said intermediate layer extending slantingly between holes of opposite plates, for the purpose described.

6. A visitor's partition of the character described comprising front and rear resistant plates provided with opposite portions for oral communication provided with non-registering holes, said plates provided with registering observation openings in adjacency to said first-named portions, filler bars between said plates forming recessed marginal walls for said first-named portions and said openings, the portions of said filler-bars forming marginal walls for said openings 10 being of greater thickness than the thickness of the balance of said filler-bars, a perforate layer provided with complemental elevations and depressions between said recessed mar-

ginal walls for said first-named portions extending across said holes and having portions extending slantingly between said plates, and shatter-resistant window sheets extending across said openings between said recessed marginal walls of greater thickness, said shatter-resistant window sheets being of greater thickness than the thickness of said formed perforate layer, and one of said plates provided with an outward bulge at said walls of greater thickness and at said window sheets, and means for releasably securing said last-named plate in association with said filler bars. 20 25 30

In testimony whereof, I have hereunto signed my name.

GEORGE J. KOSTERS.
